METAL BARREL

Charles Seitz, Utica, N. Y., assignor, by mesne assignments, to The Bossert Company, Inc., Utica, N. Y., a corporation

Application March 7, 1934, Serial No. 714,439

3 Claims. (Cl. 220—10)

This invention relates to a metal barrel of the type having an inner receptacle of metal and an outer casing of metal.

The purpose of my present invention is to provide a new and improved form of metal barrel of the type designated and also to point out the process or method of making the same.

Further purposes are to provide a barrel of the type mentioned which is formed of a minimum number of parts and which parts are so shaped, combined and assembled as to render the article readily and economically manufactured, but strong and durable in use and well adapted to resist the hard usage which such articles receive and at the same time keep the liquid therein in good condition and well insulated so as to keep the contained liquid at the desired temperature for a long time.

Further purposes and advantages of the invention will appear from the specification and claims herein.

Fig. 1 is a longitudinal central sectional view of a completed metal barrel embodying this invention.

Fig. 2 is a detailed sectional view of the adjacent edges of the two halves of the receptacle before being brought together and Fig. 3 is a similar view after said parts have been brought together and fastened to each other.

Fig. 4 is an enlarged sectional view of the adjacent edges of the four main parts of the barrel after the two casing halves have been assembled about the receptacle and Fig. 5 is a similar view after the edges of the casing halves have been joined together and to the flanges of the receptacle by welding. Fig. 6 is a perspective view of half of a barrel when cut longitudinally.

Fig. 7 is an enlarged vertical sectional view of the tap bushing and adjacent parts of the inner receptacle and outer casing.

Referring to the drawings in a more particular description it will be seen that this barrel comprises an inner metal receptacle 10 in the form of a slightly tapering barrel and made from two pot-shaped halves 11 and 12 substantially similar in construction and an outer metal casing 13 also formed of two substantially similar halves 14 and 15.

The receptacle halves 11 and 12 are preferably each formed integrally from a single piece of sheet metal of the proper sort, size and thickness and shaped as by stamping or pressing so as to each be pot-shaped in form and each having its side wall 16 tapering or curving slightly

to be larger at the center of the barrel and with the free or joint edge of the side wall 16 provided with an outwardly extending flange 17. Preferably the heads or ends 18 of the receptacle halves join or merge with the adjacent smaller ends of the walls 16 with a rounded or curving junction 19. This curved junction 19 makes the receptacle better adapted to be kept clean through avoiding a sharp angle on the inside of the barrel and also is the better practice in the metal working of drawn or stamped metal and also gives a wide, rounded or curved surface to be engaged on the outside of the receptacle by the inner surface of the casing as hereinafter described. The ends or heads 18 of the receptacle halves 11 and 12 are conveniently formed alike even as to having both heads provided with a depression 20 adapted to receive the inner end of a sleeve or tap bushing 21. Of course only one receptacle half as the half 11 is cut and equipped with this bushing 21 while the other receptacle half 12 has its recess 20 remain intact and forms the low spot into which the tap rod extends so as to entirely empty the barrel. The integral flanges 17 extending outwardly from the free edges or larger ends of the receptacle halves 11 and 12 extend outwardly in a plane at right angles to the longitudinal axis of the barrel so that when two receptacle halves are brought together the opposing faces of the two flanges or at least a considerable portion of the said opposing faces will fit closely and smoothly together and adapt the two halves of the receptacle to be permanently and readily joined together as by a welding process, preferably a stitch-welding process, operating to unite the opposing flanges. It will be understood of course that the two halves and particularly the entire circumference of the opposing meeting edges of the two flanges will be pressed together closely enough to form not only a good mechanical joint, but also a liquid-tight and air-tight joint. The parts at this stage of manufacture are represented by the detail sectional view Fig. 3.

Preferably the outer or non-engaging surface 22 of each flange 17 of the receptacle halves will be provided with a recess 23 reaching entirely around the receptacle except where interrupted by the insertion of the bung piece 24. This recess 23 is conveniently and preferably formed by making each flange 17 with a roughly semi-circular or curved rib 25 projecting away from the engaging surface of the flange or in other words, projecting out from the outer or non-en-

gaging face 22 of the flange. Preferably this rib 25 is intermediate the width of the flange more or less as shown particularly in Figs. 2 to 5 so that there is left a wide zone as at 26 immediately adjacent the side walls of the receptacle where the metal of both flanges will be in close contact and so easily welded. Also preferably there will be outside the rib 25 another zone as 27 where an appreciable width of the flanges come together closely and may be welded at the same time the zone 26 is welded or at a later time as desired. The recesses 23 open outwardly on a slant away from the barrel but with each recess facing towards the head of its half of the receptacle. This is for a purpose that will be explained hereinafter.

The outer casing 13 as already suggested has its halves 14 and 15 formed of sheet metal and preferably these casing halves are each formed from a single piece of sheet metal suitably formed as by stamping or pressing. The casing 13 is more distinctly barrel-shaped in form, that is, it bulges outwardly more at its center than does the receptacle 10. Each casing half is formed so as to have a side wall proper 28, an end or head 29 and connecting these parts a chime 30 which is U-shaped or loop-shaped when seen in transverse section at either edge of the barrel.

The side walls proper 28 of each half of the casing are shaped adjacent their smaller ends with a curve or rounded concave face 31 on the inside to closely fit the rounding zone or rounding junction 19 on the outside of the receptacle.

From this zone where the outer casing closely engages the junction point of the side walls and ends of the inner receptacle, the side wall 28 of the outer casing slants away from the side wall 16 of the inner receptacle as it extends towards the larger or central part of the barrel and these parts remain so spaced apart for the balance of the length of both side walls. Preferably, however, this slanting of the wall 28 of the casing is not regular, but is irregular in that there is a decided outward projection or protuberance as at 32 a little ways towards the center of the barrel from the engaging zone formed between the rounded surfaces 19 and 31. The part 32 preferably has an inwardly extending reinforcing bead 32a. Beyond this raised part or protuberance 32 the wall 28 is reduced relatively for a zone as at 33 and then there is another raised or enlarged zone 34 after which is a smaller narrower zone 35. The raised zones 32 and 34 correspond roughly to the projections of the metal hoops upon the wooden staves of a wooden barrel and render the metal barrel similar in appearance to a wooden barrel. These raised zones form intervening shoulders or steps in the casing side which tend to strengthen the casing of the metal barrel and prevent its being pressed or forced inwardly in hard usage. These projections also aid in the handling of the barrels and particularly in the handling or moving of the barrels in factories or for instance in breweries where the racks and runways are already shaped to fit the common wooden barrels having metal hoops.

Preferably the extreme free edge of each side wall 28 is turned or slanted inwardly somewhat as at 36 so that when a casing half is placed in position upon its end of a receptacle the edge of this turned band 36 will enter and preferably engage the bottom of the recess 23 already mentioned as being formed in the outer or back side 75 of each flange 17 of the inner receptacle halves.

When two opposite casing halves have thus been placed in proper position against the opposite parts of a receptacle, the parts will be in the position shown in the enlarged sectional view Fig. 4 with an inturned band 36 of each of the two casing halves entering and preferably engaging the oppositely located recesses 23 of the already assembled receptacle.

With these parts securely held in position a welding operation, preferably an arc welding operation, is carried out so as to form a strong, heavy weld uniting the opposing bands 36 of the outer casing halves to the adjacent flanges of the receptacle and also more securely uniting the outer parts of the said two flanges 17 of the two halves of the receptacle even if those outer parts have theretofore been united by the preliminary welding process used to initially join the two parts of the receptacle. Fig. 5 shows the condition of these parts after such a welding operation has been carried out and particularly shows that the material added during such welding operation and the heating of the adjacent parts of the barrel have made a homogeneous joint between the outer parts of the two flanges of the inner receptacle and also between the adjacent parts of the two halves of the outer casing.

It will be seen that this central joint between the two parts of the receptacle and the two parts of the casing joins all these four parts together 30 and so the center of the inner receptacle is braced and held in spaced and concentric relation relative to the outer casing by the two flanges 17 of the receptacle projecting out to and substantially into line with the outer wall of the outer 35 casing and permanently welded thereto.

The chime 30 already mentioned as connecting the smaller end of each each casing side wall 28 and its head or end 29 is formed by the metal being shaped beyond the interengaging zones 31 and 19 of the barrel to have a zone 39 projecting lengthwise of the barrel for an appreciable distance and then turned inwardly for a less distance forming a ring 40 upon which the barrel stand when on end and thereafter the metal is 45 turned back towards the inside of the barrel forming a zone as 41 extending towards but not reaching the head or end 18 of the receptacle. The zone 41 preferably slants outwardly about parallel with zone 39 to provide a better hand 50 hold of the barrel. From the zone 41 the metal curves towards the slightly outwardly bulging head 29 already mentioned. This loop or U-shaped form made by the parts 39, 40 and 41 forms an inherently strong rigid chime reaching 55 entirely around each end of the barrel. If desired this may be further re-inforced by a ring 60 preferably of angle-shaped metal 42 placed in the bottom of the chime and securely fastened in place against the ring 40 and against the outer wall 39 of the chime by suitable welding.

It will be understood that each half as 11 and 12 of the receptacle will be provided with a semi-circular opening placed opposite each other to allow the fastening thereto of the bung piece 24. Of course through the space occupied by this bung piece there are no flanges 17 but the bung piece through having the inturned edges 43 of the outer casing securely fastened thereto forms a 70 reinforcement at this place directly connecting the inner receptacle and the outer casing. The outer casing half as the half 13 which is to be placed opposite the sleeve or bushing 21 is provided with an aperture preferably having in- 75

turned edges to be suitably fastened as by welding to said sleeve member 21. Preferably the bilge or bulging part of the outer casing is further reinforced by each half of the outer casing having a specially formed channel-shaped ring of metal 44 provided and secured to the inside of the said casing half preferably within the zone 34. This reinforcing ring has its loop or connecting portion 45 towards but spaced from the inner receptacle and its two legs 46, preferably slant somewhat away from each other as they extend toward the outer casing and at their outer ends the legs 46 are provided with oppositely turned feet 47 substantially parallel to the loop portion 45 and resting flat against and securely fastened to the said casing as by welding. It will be seen that these rings of channel-shaped metal with their braced and securely fastened legs will greatly strengthen the casing at the middle of the barrel and will tend to prevent any bending or distortion of the inner receptacle sufficient to injure the inner receptacle. These two reinforcing rings being at the largest zones of the barrel will take the main strain when the barrel is dropped flatwise or is being rolled. These two reinforcements also by being closely adjacent on opposite sides of the main joint between the four parts of the barrel at its center will operate to protect the said encircling main joint of said main parts from any injury or distortion that might result in breaking the tightness of said joint. It will be understood too that these reinforcing channel-spaced rings 44 are placed and secured within the casing halves before the casing halves are mounted upon the inner receptacle and accordingly it will be seen that these reinforcing rings can be very securely welded or otherwise fastened in place to the casing halves inasmuch as access is at that time readily had to both the inside and outside of the casing halves.

Preferably a packing 48 as of some strong but slightly resilient and heat-insulating material is interposed between the central parts of the head of the casing 29 and the end or head 18 of the inner receptacle at both ends of the barrel. This allows the great strength of the outer casing head and chime to be utilized to brace the thinner head of the inner receptacle from any bulging or distortion such as might be caused by dropping the barrel endwise when filled. The packing being slightly resilient and heat-insulating gives a sufficient contact between these two parts without interfering with the heat-insulation maintained throughout practically all of the rest of the barrel due to the dead air space existing between the outer casing and the receptacle.

It will be noted that when the barrel is rolled or moved flatwise on the largest part of its bilge the contact with the floor will be against the largest zones 34-34 spaced away from the central joint of the barrel. This operates to relieve the said central joint from direct engagement with the floor or with obstructions upon the floor and also operates to minimize the conduction of heat through said joint to the floor as would happen if the joint itself rested upon the floor.

It will be seen that the inner receptacle is supported within the casing by the engagement of the inner receptacle junction zones 18 fitting the correspondingly curved concave zones 31 at each end of the barrel. It will be noted further that these zones are well adapted to take both side strain and end strain. Furthermore, the main central joint between the sections of the barrel also brace the receptacle within the casing and is

well adapted to take a large part of the side strain and also of any end strain that may be placed upon the barrel.

On account of the extent by which the chime 30 extends beyond the sides and head of the barrel and on account of the outer projection of the zones 32, direct contact of the casing with the ground or floor cannot be had at the casing opposite the zone 31. This is illustrated by the straight line placed in the lower left hand part 10 of Fig. 1 and extending past the zone 32 and the chime 30. In case the barrel were placed or dropped against the floor at the angle represented by said figure and said straight line 49-49, it will be seen that the strain of contact would 15 not be taken directly against the zone 31, but would be taken by the raised zone 32 and the chime 30.

The central aperture 50 of the tap bushing 21 tapers to be slightly smaller as it proceeds inwardly to fit the usual tapering tap bushing plug which is ordinarily of wood. In order however to hold said plug more securely against accidental displacement I provide about midway the depth of the aperture 50 a groove 51 cut back into the 20 wall of the bushing. The outer part of this groove recedes sharply back into the bushing forming a shoulder 52 the outer part of which is substantially at right angles to the adjacent or outer part of the wall of the aperture 50. The 25 inner part of this groove then slants or curves gently back towards the line of the inner half of the wall of the bushing so as to smoothly merge as at 53 with the said inner half of the wall of the main aperture. In other words this 30 groove as will appear particularly from Fig. 7 is in the shape roughly of a half of a conventional heart-shaped figure with the decided shoulder 52 at the outer edge of the groove and the smooth merging zone 53 at the inner part of the groove. 35 It will be seen that then as a regular tapering tap plug 61 is forced into this tap bushing the inner half of the plug will pass the slanting or rounding zone 53 without being burred outwardly. After liquid has been placed in the barrel the 40 liquid will cause the wood of the plug to swell outwardly more or less into the groove 51 and this outward swelling of the plug will particularly engage back or to the inside of the sharp shoulder 52 of the bushing (as indicated by the 45 part of the plug 61 in Fig. 7) and act as a lock to prevent accidental or premature displacement of the plug. When it is desired however to remove the plug sufficient power applied in the usual way to the plug by a proper device will 50 accomplish the purpose. 55

The bung-piece or bushing 24 has its central tapering aperture 54 provided with a similar re-entering groove 55 having a relatively sharp shoulder 56 at its outer side and a merging, slanting or curved zone 57 returning to the regular slant of the inner part of the main aperture all for a similar purpose and operating in the same way to retain the bung against premature or accidental displacement. Referring again to the 60 detailed sectional view Fig. 7 of the tap bushing and the adjacent part of the barrel it will be seen that the periphery of the bushing is provided at its outer part with a reduced diameter leaving a flat step or ledge 58 and an under-cut outer 65 wall 59. Into the angle thus formed extends the inwardly turned flange 60 of the end 29 of the outer casing with the edge of the metal engaging the flat ledge 58 and with the face of the flange 60 as close as practicable to the undercut 70 75

outer wall 58. The close engagement of the flange 60 against the undercut wall 59 especially when the parts are welded operates to strengthen the joint here made against loosening these parts 5 when strain is placed upon the bushing as by the driving in of the tap bushing plug.

Similarly the inturned halves of flanges 43 semi-circular on each half of the outer casing fit closely underneath the undercut peripheral 10 wall 62 of the bung piece or bung bushing 24 and when the two halves of the outer casing are welded in place at the main central circumferential joint these inturned flanges 43 make a very rigid support for the said bung piece against any 15 strain tending to force the bung piece inwardly. Such inward strain is sometimes placed upon the bung piece when the bung is being forced into place. This direct mechanical bracing of the bung piece is rendered still more secure by the 20 welding of the flange 43 of the outer casing to the bung piece 24 but the tight engagement of the flanges 43 encircling the undercut wall 62 holds the bung piece or bushing 24 in place even without this welding and will so hold it even if 25 this welded joint should be damaged by excessive strain.

What I claim as new and desire to secure by Letters Patent is:

1. In a metal barrel the combination of an inner receptacle consisting of two pot-shaped 30 halves, each having an outwardly extending flange at the free end of the side wall, said flanges engaging and being fastened face to face, each flange having on its non-engaging face a recess 35 opening outwardly and towards its end of the

barrel and a barrel-shaped casing consisting of two halves having the free edges of the casing halves entering the said recesses of the receptacle flanges and fastened to said flange and to each other.

2. In a metal barrel the combination of an inner receptacle consisting of two pot-shaped halves, each having an outwardly extending flange at the free end of the side wall, said flanges engaging and being fastened face to face, 10 each flange having intermediate its width on the non-engaging face a bead forming with the outer part of the flange a recess opening outwardly and towards its end of the barrel and a barrel-shaped casing consisting of two halves having 15 the free edges of the casing halves entering the said recesses of the receptacle flanges and fastened to said flange and to each other.

3. A metal barrel comprising a fluid container composed of a pair of like parts each having a 20 continuous outwardly extending flange at its open end, said flanges being provided with laterally extending projections intermediate their ends and being welded to each other to provide a fluid tight joint, an outer shell comprising two 25 like parts adapted to fit in spaced relation thereto, having their edges at their open ends abutting said flanges of said inner container and also lying against the outer surfaces of said projections, said edges of said outer shell parts 30 and said flanges of said inner container all being secured together for securing said outer shell parts together and to said inner container.

CHARLES SEITZ. 35
